UNITED STATES PATENT OFFICE

OTTO E. TRAUTMANN, OF ROCHESTER, NEW YORK, ASSIGNOR TO BAUSCH & LOMB OPTICAL COMPANY, OF ROCHESTER, NEW YORK, A CORPORATION OF NEW YORK

DESIGN FOR A BINOCULAR

Application filed January 16, 1931. Serial No. 38,331. Term of patent 14 years.

To all whom it may concern:

Be it known that I, OTTO E. TRAUTMANN, a citizen of the United States and a resident of Rochester, county of Monroe, and State of New York, have invented a new, original, and ornamental Design for Binocular, of which the following is a specification, reference being had to the accompanying drawing, forming a part hereof.

Fig. 1 is a top plan view of a binocular showing my new design.

Fig. 2 is a rear elevation of same.

Fig. 3 is a front elevation of same.

Fig. 4 is a side elevation of same.

I claim:

The ornamental design for a binocular substantially as shown.

OTTO E. TRAUTMANN.
